UNITED STATES PATENT OFFICE.

EUSTICE E. DICKERSON, OF FORT WORTH, TEXAS.

BOLL-SEPARATOR.

1,185,885.

Specification of Letters Patent. Patented June 6, 1916.

Application filed August 16, 1915. Serial No. 45,644.

To all whom it may concern:

Be it known that I, EUSTICE E. DICKERSON, a citizen of the United States, residing at Fort Worth, in the county of Tarrant and State of Texas, have invented certain new and useful Improvements in Boll-Separators, of which the following is a specification.

My invention has relation to an improvement in boll separators of that type or class wherein the cotton bolls after being subjected to the action of a breaker or crusher are subjected to air suction to separate the cotton from the bolls and in such connection it relates broadly to means whereby after the boll is broken the cotton is removed from the hulls or bolls by suction prior to its passage through the cleaner and the gin.

So far as I am aware the usual procedure with bolly cotton is to break the boll, pass the broken boll through a cleaner to eliminate a portion of the internal and extraneous dirt, trash, and bolls and thereafter pass the cleaned cotton through a huller gin wherein a picker roll mechanism serves to remove the coarse dirt and hulls from the cotton before the cotton enters the roll box of the gin. This procedure is both expensive and ineffectual. It is based upon an erroneous theory in that it contemplates the passage of hully or bolly cotton through the cleaner which cleaner is primarily for the purpose of loosening the fiber to remove small particles of dirt inside as well as on the outside of the cotton.

My present invention contemplates the provision of a complete organism or machine designed to remove the bolls or hulls from the cotton prior to its entrance to the cleaner and it also contemplates an arrangement of means in such an organism whereby the machine may be introduced into the ordinary chain of operations and particularly into an arrangement of instrumentalities constituting a plant wherein the cotton in transit from the wagon or storage bin is conveyed first under suction and thereafter under either suction or air pressure through said instrumentalities to the gins.

In the carrying out of my invention there

is interposed between the wagon or raw cotton supply and the main cleaning apparatus, a boll breaker and a boll separator. The boll breaker may be of any preferred construction in so far as its mechanism is concerned provided it discharges directly into the boll separator. The boll separator, however, both as to construction, arrangement, and manner of operation is peculiarly my invention and broadly considered it comprises a conveying mechanism arranged to receive the broken bolls discharged from the boll breaker, said conveyer being suitably arranged to not only convey the cotton bolls away from the outlet of the boll breaker, but to permit of ready separation, by suction of the major portion of the cotton from the bolls at approximately the point of discharge from the boll breaker. In the construction and arrangement of said conveyer the predominant requirements are that the conveyer shall perform its function as a means for supporting and conveying the bolls and shall also perform the additional function of a screen wherethrough the cotton staple may be withdrawn from the bolls and conveyed under suction to the cleaner.

The nature and scope of my invention will be more fully understood from the following description taken in connection with the accompanying drawings forming part hereof, in which—

Figure 1, is a side elevational view partly sectioned of a boll breaker and a boll separator embodying the main features of my invention. Fig. 2, is a top or plan view thereof, partly broken away, and Fig. 3, is a cross-sectional view taken on line *a—a*, Fig. 1.

Referring to the drawings, 1 represents the inlet pipe for raw cotton from a wagon or suitable source of raw-cotton supply and 2 represents a boll breaker of any desired construction and arrangement.

The boll breaker 2 is supported upon a boxlike frame 3 and discharges the broken bolls directly thereto and within the same.

In the box 3 is arranged to travel a conveyer 4 of preferably endless construction. This conveyer 4 should form a means for

receiving and supporting the cotton bolls and should be formed so as to permit of the cotton staple being drawn, to a chamber 5 under suction, from the bolls which cannot 5 pass through said conveyer 4 to said chamber 5. The chamber 5 is connected by pipe 6 with a fan 7 and is in fact a suction chamber.

In the preferred form of conveyer 4 as 10 illustrated in the drawings, the conveyer 4 consists of a series of endless bands or chains, each consisting of triangular (in cross section) hollow links 8 connected at either end by pintles 9 which are supported 15 on the horizontal portions of the travel of the conveyer by wheels 10. These wheels 10 serve as a means to separate adjacent chains from each other, the spaces 11 thus formed permitting of the passage of the 20 cotton staple from the boll when the conveyer 4 is passing below the boll breaker 2 and in front of the chamber 5. At certain intervals certain of the links 8 carry the upright rubber strips 12 which serve as valves to close 25 the box-like frame 3 against entrance or escape of air while the conveyer is traveling in said box 3.

The return portion of conveyer 4 also travels through a box-like frame 13 similar to 30 but below frame 3. When the conveyer 4 travels through the lower frame 13 the wheels 10 ride upon the roof of the box 13 whereas when the conveyer travels through upper box 3 the wheels 10 ride on the floor 35 of box 3.

The lower box 13 has an opening 14 in its base and this opening is screened by a series of rollers 15 transversely arranged across said opening. As the bolls (with some cotton 40 still adhering thereto) pass with the conveyer 4 into lower box 13 they are conveyed by the flaps or strips 12 to and over these rollers 15. Below the rollers 15 is arranged a suction chamber 16 communicating with 45 suction pipe or flue 6. As the bolls pass or roll over rollers 15, the loose cotton is drawn or sucked into chamber 16, and passes from thence into pipe 6 and thereafter into cleaner or similar instrumentality not shown.

50 All the chains forming the conveyer 4 are preferably connected side by side by the pintles 9 and wheels 10, and at either end of boxes 3 and 13 is arranged a series of sprockets 17 each of which supports a chain. Each 55 series of sprockets 17 is supported upon a shaft 18 and either of the shafts 18 may be driven in any suitable manner from any desired source of power.

In the operation of this device the broken 60 bolls from the boll breaker 2 are discharged upon a conveyer 4 which by reason of the ridged or angular character of the parallel links 8 firmly hold and support said bolls. The staple is drawn from the bolls through

spaces 11 in the conveyer into the chamber 65 5 and pipe 6 when suction is applied to said pipe by fan 7.

Having thus described the nature and objects of my invention what I claim as new and desire to secure by Letters Patent, is— 70

1. In a device of the character described, a boll breaker, a conveyer arranged to receive the cotton and bolls discharged from said boll breaker, open spaces formed in the base of said conveyer to convert said conveyer into a screen, and suction means for withdrawing the cotton from said bolls through the said spaces of the conveyer. 75

2. A boll separator comprising a traveling conveyer having a face arranged to receive and support the bolls and cotton and a perforated base constituting a screen, combined with a chamber arranged below and in communication with the screen base of the conveyer and means for creating suction in 80 said chamber to thereby withdraw the cotton from the bolls through the screen base of the conveyer and into said chamber. 85

3. In a device of the character described, a box like frame having an opening, and an 90 endless conveyer for the cotton, traversing the frame above said opening, said conveyer formed of a series of endless chains separated from each other to form intervening spaces traversing said opening in the frame, 95 combined with means for creating suction in said opening below the intervening spaces in the conveyer.

4. In a device of the character described, a box like frame having an opening in its 100 base, a means for creating suction through said opening, an endless conveyer traveling within said frame and over said opening, said conveyer comprising a series of endless chains arranged side by side and separated 105 from each other by intervening spaces traversing the opening.

5. In a device of the character described, a box like frame, having an opening in its base, a means for creating suction through 110 said opening, an endless conveyer traveling within said frame and over said opening, said conveyer comprising a series of endless chains, each provided with links triangular in cross section, a series of pintles connecting the links of corresponding chains together, and a series of wheels on said pintles arranged to separate the chains by intervening spaces traversing the conveyer. 115

6. In a device of the character described, 120 an endless conveyer comprising a series of endless chains separated from each other by intervening spaces traversing the conveyer, a box like frame traversed by the upper portion of said conveyer, a box like 125 frame traversed by the return portion of said conveyer, and a means for creating suction below the base of each box like frame.

7. In a device of the character described, an endless conveyer comprising a series of endless chains separated from each other by intervening spaces traversing the conveyer, 5 a box like frame traversed by the upper portion of said conveyer, a box like frame traversed by the return portion of said conveyer,

and a means for creating suction below the base of each box like frame, and a series of flaps carried by said chains and serving as 10 air valves within the box like frame.

In testimony whereof I have signed my name.

EUSTICE E. DICKERSON.
